(57) **CLAIM**

The ornamental design for a vertical electrical connector, as shown and described.

DESCRIPTION

FIG. 1 is a top, right, front perspective view of a first embodiment of a vertical electrical connector showing my design; FIG. 2 is another top, right, front perspective view of thereof; FIG. 3 is a bottom, left, front perspective view thereof; FIG. 4 is a top, right, rear perspective view thereof; FIG. 5 is a bottom, left, rear perspective view thereof; FIG. 6 is a right side elevation view thereof; FIG. 7 is a left side elevation view thereof; FIG. 8 is a front elevation view thereof; FIG. 9 is a rear elevation view thereof; FIG. 10 is a bottom plan view thereof; and FIG. 11 is a top plan view thereof.

FIG. 12 is a top, right, front perspective view of a second embodiment of a vertical electrical connector showing my design; FIG. 13 is another top, right, front perspective view of thereof;

FIG. 14 is a bottom, left, front perspective view thereof; FIG. 15 is a top, right, rear perspective view thereof;

FIG. 16 is a bottom, left, rear perspective view thereof;

FIG. 17 is a right side elevation view thereof;

FIG. 18 is a left side elevation view thereof;

FIG. 19 is a front elevation view thereof;

FIG. 20 is a rear elevation view thereof;

FIG. 21 is a bottom plan view thereof; and,

FIG. 22 is a top plan view thereof.

The even-broken line in the figure drawings is included to show unclaimed environment and forms no part of the claimed design. The dash-dot broken line represents the boundary of the claimed design.

In a preferred embodiment, the nature of this product is an electrical component that can take the form of a vertical electrical connector and a connector housing therefor.
